UNITED STATES PATENT OFFICE.

JAMES A. DILLON, OF CHICAGO, ILLINOIS, ASSIGNOR, BY MESNE ASSIGNMENTS, OF ONE-HALF TO NATIONAL LAUNDRY MACHINERY CO., OF CHICAGO, ILLINOIS, A CORPORATION.

STEAM-CONDENSER.

No. 813,486.

Specification of Letters Patent.

Patented Feb. 27, 1906.

Application filed June 26, 1905. Serial No. 266,918.

To all whom it may concern:

Be it known that I, JAMES A. DILLON, a resident of Chicago, in the county of Cook and State of Illinois, have invented certain new and useful Improvements in Steam-Condensers, of which the following is a full, clear, and exact description.

The invention relates to steam-condensers, and designs to provide improvements in the type of condenser set forth in Letters Patent of the United States No. 582,813, granted to me May 18, 1897.

One object of the invention is to provide an improved construction in which the heat units of the exhaust-steam are better utilized in heating water.

Another object of the invention is to provide improved means for spreading water for contact with the steam.

Another object of the invention is to provide improved means for separating the oil suspended in the steam from the steam.

Lastly, the invention designs to provide an improved construction of combined condenser, separator, and heater.

The invention consists in the several novel features hereinafter set forth, and more particularly defined by claims at the conclusion hereof.

In the drawings, Figure 1 is a central vertical section of a steam-condenser embodying the invention. Fig. 2 is a similar view showing a modified form of the invention. Fig. 3 is a horizontal section taken on line 3 3 of Fig. 2.

10 denotes a cylindrical casing of the condenser, within which is provided a steam-chamber 11. The casing comprises a top 12, removably secured to the body of the casing for convenience in cleaning the parts therein. The lower portion of the casing is tapered, as at 10'. A cylindrical wall 22, having a conoidal lower portion 23, forms the inner wall of the chamber for the passage of steam to the condensing-chamber and also forms the surrounding wall of the condensing-chamber. A pipe 15 conducts exhaust-steam to the condenser and is provided at its upper end with an elbow 16, which directs the steam into a separating-pocket near the lower end of the steam-chamber and formed between the lower conoidal portion 23 of the inner wall of the steam-chamber and a vertical wall 13.

At the bottom of wall 13 a channel is formed in which oil extracted from the steam is collected, said channel being formed by forming an upwardly-extending flange 13' at the inner edge of the bottom of wall 13. A space 14 is formed between said channel and wall 23 for the passage of steam. An oil-pipe 20 for conducting the oil extracted from the steam to any desired point is connected to the bottom 17 of the casing. The oil collected in the channel in the separating-pocket passes through a pipe 20' to pipe 20. Steam directed into the separator pocket or chamber through elbow 16 passes around the lower portion of wall 23, and thereby comes in contact with the walls of the pocket, which causes the oil to adhere to the walls of the pocket, and thus effects separation of a large portion of the oil from the steam. The oil which collects around the lower portion of wall 23 gravitates into the lower portion of chamber 11 and thence to pipe 20. The oil collected in the channel at the bottom of the separator-pocket passes by pipe 20' to pipe 20. The purpose of providing the separator pocket or chamber around the lower portion of the wall of the condensing-chamber is to heat said wall so the water passing thereover will be heated.

Wall 22 is arranged inside of chamber 11, around which the steam circulates and which extends to a point near the top of the casing, so the steam in chamber 11 must pass to the top of the chamber before it is brought in contact with the water for condensation. The lower portion of wall 23 has connected thereto at its reduced lower end an outlet-pipe 24, which conducts the purified heated water to any desired point. A pipe 25 conducts cold water onto a spreader-plate 26, which is preferably of the form shown and is provided with an upwardly-extending annular wall 27, having perforations 28 therein. The water delivered onto the spreader passes through perforations 28 to the outer edge of the spreader, where it is directed against wall 22. The water passes from the spreader in a thin sheet, and the steam will be condensed and absorbed thereby. The water passing from the spreader is heated by the exhaust-steam and passes into contact with the heated walls 22 and 23, so the temperature is materially raised because the wall is heated on

the outer side by steam passing upwardly in chamber 11. A hood 30 is arranged above the spreader to prevent the steam from coming into direct contact with the water on the 5 spreader and the formation of scale on the inner portion of the spreader. The capacity of perforations 28 is substantially equal to the capacity of pipe 25 under normal pressure. Should pressure in pipe 25 become 10 greater, so a larger quantity of water will be supplied, the water will flow from the upper edge of the overflow flange or ring 27 and be discharged around the spreader. A stack 29 for the admission of air extends upwardly 15 from the separator through the top 12 of the casing.

The operation will be as follows: Exhaust steam containing oil in suspension is conducted to the separator-pocket by pipe 15. A 20 large portion of the oil is there extracted, and the steam passes from said chamber around the lower edge of the oil-channel into steam passage or chamber 11, wherein the remainder of the oil is extracted, which passes to the 25 bottom of the casing. In the separating chamber or pocket effective separation of the oil from the steam occurs therein and also in the lower portion of chamber 11, because the steam does not rise quickly in said chamber 30 before coming in contact with the walls of the separator-pocket. The steam heats the walls of the pocket and particularly the lower portion of wall 23 of the condensing-chamber, over which the purified water 35 passes. The steam rising in chamber 11 after the oil has been extracted passes over the upper edge of wall 22 and into the chamber therein. The steam passing upwardly in chamber 11 heats wall 22, so the water in the inner chamber will be heated by the steam in chamber 11. When the steam has risen in chamber 11, it passes over the upper edge of wall 22 and is condensed by the water flowing over spreader 26, which is heated thereby. 40 The water after it passes from the spreader is brought into contact with the inside of walls 22 and 23, so that it will be heated before it passes to outlet 24.

It will be observed that the steam-inlet is 45 located at or near the bottom of the steam-chamber and in its passage, heats the inner walls of said chamber, and as a result the temperature of the water is materially raised before it leaves the condenser, and thus the heat units of the exhaust-steam are utilized to 50 heat the purified water after it has served to condense the steam. Another advantage of the improved construction is that the flow of water is not limited and if excess is provided 55 by pipe 25 the water will overflow wall 27. The scale usually forms along the outer edge of spreader 26, from which it can be readily removed when desired. By providing a separator-pocket the oil is extracted from the 60 steam in the lower portion of the condenser,

and the steam does not rise rapidly enough to carry the oil with it into the condensing-chamber.

In Figs. 2 and 3 is illustrated a modified form of the invention in which a baffle or deflector extending across the lower portion of the steam-chamber is provided in lieu of the separator-pocket hereinbefore described. A pipe 31 conveys exhaust-steam to an oil-trap 32, from which the steam passes by pipe 34 to an elbow 35. Steam is directed into chamber 11 by elbow 35 and passes around the lower portion of the chamber until it encounters deflector 18. By projecting the steam against the walls of the jacket and the baffle 80 the progress of the steam, with the oil therein, is arrested sufficiently so that the oil will be separated from the steam and remain in the lower portion of chamber 11. Baffle 18 is inclined or curved at its upper end to reversely direct the steam emanating from the steam-inlet. The baffle is cut away, as at 85 19, to provide a passage for the oil from both sides thereof to pipe 20^a, whereby the oil is carried away. It will be seen that in this 90 form of the invention the steam enters the lower portion of the condenser and passes around the condensing-chamber to the upper portion of the condenser before it passes into the condensing-chamber.

The invention is not to be understood as restricted to the precise details set forth, but may be modified without departing from the spirit and scope of the invention.

Having thus described the invention, what I claim as new, and desire to secure by Letters Patent, is—

1. In a condenser the combination of a casing having a chamber therein for the passage of steam, a steam-inlet near the bottom thereof, a wall within said chamber in which a condensing-chamber is formed, said chambers being in communication with each other near the top thereof so the steam entering at the bottom will heat the water flowing through the condensing-chamber before the steam passes into the condensing-chamber, and a pipe for conducting water to the condensing-chamber.

2. In a condenser the combination of a casing having a chamber therein for the passage of steam, a steam-inlet near the bottom thereof, a wall within said chamber in which a condensing-chamber is formed, a separator-pocket around the condensing-chambers, said chambers being in communication with each other near the top thereof so the steam entering at the bottom will heat the inner wall, and a pipe for conducting water to the condensing-chamber.

3. In a condenser the combination of a casing having a chamber therein for the passage of steam, a steam-inlet near the bottom thereof, a separator-pocket near the bottom of the casing, a wall in said chamber in which a con-

densing-chamber is formed, said chambers being in communication with each other near the top thereof so the steam entering at the bottom will heat the inner wall and the water 5 therein, a pipe for conducting water to the condensing-chamber, and an oil-pipe connected to the bottom of the casing.

4. In a condenser the combination of a casing having a chamber therein for the passage 10 of steam, a steam-inlet near the bottom thereof, a separator-pocket near the bottom of the casing, a wall in said chamber in which a condensing-chamber is formed, said chambers being in communication with each other near 15 the top thereof so the steam entering at the bottom will heat the inner wall and the water therein, and a pipe for conducting water to the condensing-chamber.

5. In a condenser the combination of a casing having a chamber therein for the passage 20 of steam, a steam-inlet near the bottom thereof, a wall in said chamber and in which a condensing-chamber is formed, said chambers being in communication with each other near 25 the top thereof so the steam entering at the bottom will heat the inner wall, said inner wall having a reduced lower portion, a separator-pocket around said reduced portion, and a pipe for conducting water to the condensing-chamber.

6. In a condenser the combination of a casing having a chamber therein for the passage 30 of steam, a steam-inlet, a wall in said chamber in which a condensing-chamber is formed, 35 said chambers being in communication with each other, a wall in the steam-chamber extending around the lower portion of said wall and forming a pocket around said wall, and a pipe for supplying water to the condensing-chamber.

7. In a condenser the combination of a casing having a chamber therein for the passage 40 of steam, a steam-inlet, a wall in said chamber in which the condensing-chamber is formed, 45 said chambers being in communication with each other, a wall extending around the lower portion of and forming a pocket around the wall of the condensing-chamber, and a channel formed at the lower edge of 50 said pocket-wall.

8. In a condenser the combination of a casing having a chamber therein for the passage 55 of steam, a steam-inlet, a wall in said chamber in which the condensing-chamber is formed, said chambers being in communication with each other, a wall extending around the lower portion of and forming a pocket around the wall of the condensing-chamber, a channel formed at the lower edge of 60 said pocket-wall, and a discharge-pipe for the oil leading from said channel.

9. In a condenser the combination of a casing within which a steam-chamber is formed, an inner wall within which a condensing-

chamber is formed and extending to a point 65 near the top of the condenser, a steam-inlet near the bottom of the condenser, a water-outlet pipe connected to the bottom of the condensing-chamber, and a water-supply pipe leading to the condensing-chamber and whereby the steam in the steam-chamber will pass upwardly from the bottom around the wall of the condensing-chamber before it passes into the condensing-chamber.

10. In a condenser the combination of a 70 casing, a pipe for supplying steam near the bottom thereof, an inner wall within which a condensing-chamber is formed and around which a steam-chamber is formed, a supply-pipe for water, and a spreader-plate in said condensing-chamber 80 onto which the water is discharged from the supply-pipe.

11. In a condenser the combination of a casing, a pipe for admitting steam, an inner wall within which a condensing-chamber is 85 formed and around which a steam-chamber is formed, a supply-pipe for water, and a spreader-plate in said condensing-chamber onto which the water is discharged from said supply-pipe, said spreader being provided 90 with a perforated flange or wall.

12. In a condenser the combination of a casing, a pipe for admitting steam, an inner wall within which a condensing-chamber is 95 formed and around which a steam-chamber is formed, a supply-pipe for water, and a spreader-plate in said condensing-chamber onto which the water is discharged from said supply-pipe, said plate being provided with 100 an upwardly-extending wall having perforations therein and over which the water can flow.

13. In a condenser the combination of a casing having a pipe for supply-steam, an inner wall within which the condensing-chamber 105 is formed and around which a steam-chamber is formed, a supply-pipe for water, a spreader-plate in said condensing-chamber onto which the water is discharged from the supply-pipe, and a hood above said spreader-plate.

14. In a condenser the combination of an outer wall or casing having a chamber therein for the passage of steam, a steam-inlet near the bottom thereof, a wall within said chamber in which a condensing-chamber is formed, 115 said chambers being in communication with each other near the top thereof so the steam entering at the bottom will heat the inner wall and the water therein, a pipe for conducting water to the condensing-chamber, and a spreader-plate in the condensing-chamber for directing the water into contact with the inner wall.
